Primary Examiner — Mary Ann Calabrese
Assistant Examiner — Mark David Wolfley

(57) **CLAIM**

The ornamental design for a sofa, as shown and described.

DESCRIPTION

FIG. 1 is a top-front-right perspective view of a sofa showing my new design;

FIG. 2 is a bottom-rear-left perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left elevational view thereof;

FIG. 8 is a right elevational view thereof;

FIG. 9 is a perspective cross-sectional view taken along line 9-9 in FIG. 3; and,

FIG. 10 is a perspective cross-sectional view taken along line 10-10 in FIG. 3.

The broken lines in the drawings are for the purpose of illustrating environmental structure, and form no part of the claimed design.

1 Claim, 10 Drawing Sheets(56)
